UNITED STATES PATENT OFFICE.

ALBERT PFLÜGER, OF BERLIN, GERMANY, ASSIGNOR TO RICHARD MOSER,
OF SAME PLACE.

CLASP FOR ALBUMS.

SPECIFICATION forming part of Letters Patent No. 289,133, dated November 27, 1883.

Application filed March 24, 1883. (No model.)

To all whom it may concern:

Be it known that I, ALBERT PFLÜGER, of Berlin, in the Kingdom of Prussia and Empire of Germany, have invented certain new and 5 useful Improvements in Clasps, of which the following is a specification.

In the album-clasps heretofore in general use the clasp is connected to the mounting-edge plate of the cover by a hinge, the parts 10 of which are soldered to the edge plates. As the soldered contact surfaces are very small, the clasps of this construction are not very durable, and require, furthermore, considerable time and labor in properly joining the parts 15 together.

The object of this invention is to furnish an album-clasp in which the defects mentioned are done away with; and it consists of a clasp in which the casing or bail, or both, are provided with eyes that project through recesses 20 of the metallic edge plates of the cover, and are engaged by a fixed pintle that is soldered to the inner surface of the edge plate, as set forth in the claims.

25 In the accompanying drawings, Figures 1 and 2 represent an end view and a front view of an album-clasp made according to my improved construction; and Figs. 3 and 4 are a side view and a front view of an album-clasp 30 with spring-cushioned casing.

Similar letters of reference indicate corresponding parts.

In the drawings, A represents a clasp or bail, and B B' the metallic plates or mountings, that are applied in the usual manner to the edges of the album-covers. The clasp or bail A is provided with eyes a a, which are inserted into recesses b b of the edge plate B', and engaged by a fixed pintle or wire, d, that 35 is soldered to the inside of the edge plate B', said wire being passed through the eyes a a,

whereby a very strong and durable hinge-connection is formed between the clasp A and edge plate B'. When the edge plate B' is fastened to the album-cover, the pintle is inter- 45 mediately between the edge plate B' and the edge of the cover, so that it may also be retained thereby without being soldered to the plate B'.

In Figs. 3 and 4 an extensible album-clasp 50 is shown, in which a casing, C, having fixed hooks e e, forms the clasp or bail. The casing C is hinged by sliding and spring-cushioned rods f f, having eyes a a, to the pintle within the edge plate B', before described. 55 The hooks e e lock onto a pintle of the edge plate at the opposite side of the cover, which edge plate is recessed for the entering of the hooks in the same manner as the opposite edge plate B of the eyes a a of the rods f f. 60

Having thus described my invention, I claim as new and desire to secure by Letters Patent—

1. In an album, a hinge device composed of the edge plate B', having recesses b b, and provided with eyes a a, in combination with a 65 single pintle, d, secured within the edge plate, substantially as described.

2. As an improvement in album-clasps, the extensible spring-cushioned casing C, provided with rods f f, having hooks e at one end 70 and pivot-eyes a a at the other, in combination with the edge plates B B', provided with recesses b b, eyes a a, and pintles d d, substantially as described.

In testimony that I claim the foregoing as 75 my invention I have signed my name in presence of two subscribing witnesses.

ALBERT PFLÜGER.

Witnesses:

ALFRED LORENTZ,
M. WALTER.
